[57] CLAIM

The ornamental design for a sheet-fed offset press, as shown and described.

DESCRIPTION

FIG. 1 is a frontal perspective view of a sheet fed offset press embodying my new design;

FIG. 2 is a rear perspective view thereof;

FIG. 3 is a front view thereof;

FIG. 4 is a left side view thereof;

FIG. 5 is a rear view thereof;

FIG. 6 is a right side view thereof; and,

FIG. 7 is a top view thereof.

The broken line showing of the control panels and handles is for illustrative purposes only and forms no part of the claimed design.
